UNITED STATES PATENT OFFICE.

JOSEPH BIJUR, OF NEW YORK, N. Y.

APPARATUS FOR CASTING OPEN-WORK STRUCTURES.

SPECIFICATION forming part of Letters Patent No. 757,721, dated April 19, 1904.

Application filed February 10, 1903. Serial No. 142,751. (No model.)

To all whom it may concern:

Be it known that I, JOSEPH BIJUR, a citizen of the United States, and a resident of the borough of Manhattan, city, county, and State 5 of New York, have invented certain new and useful Improvements in Apparatus for Casting Open-Work Structures, of which the following is a specification accompanied by drawings.

10 My invention relates to apparatus for casting open-work structures or grilles from lead or other suitable material for making storage-battery plates and for other uses; and the objects of my invention are to enable such grilles 15 to be readily and quickly cast by practicable means.

Further objects of my invention are to avoid a multiplicity of fitting surfaces in the casting apparatus and render the construction 20 of the parts simple and at the same time strong and efficient in operation.

Further objects of my invention will hereinafter appear; and to these ends my invention consists of apparatus for carrying out 25 the above objects embodying the features of construction, combinations of elements, and arrangement of parts having the general mode of operation substantially as hereinafter fully described and claimed in this specification 30 and shown in the accompanying drawings, in which—

Figure 1 is a front elevation of hand-operated apparatus embodying my invention. Fig. 2 is a front elevation or face view with the 35 cover removed of hand-operated apparatus embodying my invention. Fig. 3 is a detail view of the product to be cast or open-work structure in the form of a grille. Fig. 4 is a longitudinal sectional view of the apparatus 40 on the line 2 2 of Fig. 2 or 6 6 of Fig. 6 with the pad-leaves of the mold thrust forward to their full extent. Fig. 5 is a longitudinal sectional view with the cover removed and with the movable pad and pad-leaves of the mold 45 retracted, so that the pad-leaves are nearly withdrawn from between the ejector-bars. Fig. 6 is a transverse sectional plan view on the line 4 4 of Fig. 4. Fig. 7 is an inner face view of the cover of the apparatus. Fig. 8 50 is a transverse sectional plan view, partly

broken away, on the line 5 5 of Fig. 5, showing the mold open—that is, with the pad-block withdrawn. Fig. 9 is a perspective view of one of the pad-leaves, partly broken away. Fig. 10 is a perspective view, partly broken away, of one of the ejector-bars. Fig. 11 is a perspective view of one of the plates that separate the pad-leaves. Fig. 12 is a side elevation, partly in section, of one side of an automatic casting-machine embodying my invention. Fig. 13 is a plan view of the same. Fig. 14 is a side elevation of the other side of the machine. Fig. 15 is a transverse sectional view of the machine looking at the face of the mold. Fig. 16 is an enlarged face view of the frame 65 of the mold. Fig. 17 is a side view of said frame shown in Fig. 16. Fig. 18 is a perspective view of a portion of the slideable pad which slides within the frame of the mold. Fig. 19 is a plan view of the mold. Fig. 20 70 is a perspective view of the movable pad with the pad-leaves, separating-plates, and ejector-bars arranged in position therein to illustrate the manner in which the parts are assembled in the mold. Fig. 21 is a face view of the 75 mold in its frame. Fig. 22 is a side view, partly in section, of the mold in its frame and showing the interior construction of the frame in dotted lines. Fig. 23 is a longitudinal sectional view of the mold and its frame 80 on the line x x of Fig. 21, the movable pad being thrust forward between the ejector-bars. Fig. 24 is a longitudinal sectional view on the line x x of Fig. 21 with the movable pad nearly withdrawn from between the 85 ejector-bars. Fig. 25 is a perspective view of one of the pad-leaves used in the automatic machine. Fig. 26 is a perspective view of one of the ejector-bars. Fig. 27 is a perspective view of one of the separating-plates. Fig. 28 is a perspective view of several of the 90 pad-leaves, ejector-bars, and separating-plates assembled as in the mold. Fig. 29 is an enlarged detail perspective view of a portion of the brush mechanism for cleaning the shav- 95 ing-knife. Fig. 30 is a side view, partly broken away, of a bar having a hooked end for prying the movable pad-block away from the frame of the mold for use with the hand-operated device. Fig. 31 is an enlarged plan 100

view of the pump. Fig. 32 is a longitudinal sectional view of the same. Fig. 33 is a front view looking at the spout on the line $y-y$ of Fig. 32 and partly broken away. Fig. 34 is 5 a detail perspective view of the composite nozzle-plate. Fig. 35 is an enlarged detail sectional view of the valve adapted to be connected to the nozzle of the pump; and Fig. 36 shows enlarged detail end and side views of 10 a portion of the brush-holder, showing the lost-motion connection for the brush-shank.

Referring to the drawings, in Fig. 3 is shown a typical casting in the form of a grille A, which will be described as comprising the 15 strips B and the ribbon C, with intermediate spaces D. According to my invention the separate strips B of the casting are formed in the recesses B' in the flat metal pieces or ejector-bars E, the outer edges of the rectangular lead 20 strips B being formed by the flat cover F. The ejector-bars E are in this instance held stationary upon the main frame G by suitable means, shown as angle-pieces H, suitably secured to the frame, as by means of the screws 25 I. In between the ejector-bars E project the pad-leaves J, all of which are in this instance simultaneously movable. The pad-leaves J are shown as separate pieces suitably clamped together in the form of one pad-block, one 30 leaf being separated from the next by means of the pad-leaf separators K. Pad-leaf covers L of considerable thickness cover the ends of the pad-block and form a seal for the metal at either end. The pad-leaf covers L, pad-leaves 35 J, and separating-plates K are held as one piece to form the pad-block by suitable means, shown as the screws O, which traverse all these different parts and clamp them tightly together. In order to afford provision for 40 the insertion of the screws O, the pad-leaves J and separating-plates K are provided with the apertures P. The parts of the pad-block having been assembled, the whole is then attached by other screws Q to a back plate R, 45 whose function is to enable the pad-block to be pushed forward and pulled back. The function of the pad-leaves J is to form the openings D in the lead casting, and for this purpose they are provided with separated 50 tongues S, which project in between the notches or recesses B' of the ejector-bars E. As shown, the tongues S are separated by the narrow notches T cut into the pad-leaves J and of the same depth as the recesses B' in the 55 ejector-bars E. By this means one lead ribbon C of the casting is connected with the next in the finished product, the notches T permitting the metal to form the continuous ribbons C in the casting.

60 As herein described, the ejector-bars E are stationary, while the pad-leaves J are movable relatively thereto; but I am not be understood as limiting myself to this relative arrangement of the parts, as the apparatus may 65 be constructed in different ways without de-

parting from the spirit of my invention. When the cover F is placed in front of the mold, as shown in Fig. 4, to close the mold, the material for casting is poured within the sprue-hole U and falls down the channels V into the well W and, rising, fills the mold. The object of having the well W is to allow the first partially-cooled metal to flow into a pocket instead of entering the mold directly. It would not be feasible to endeavor to fill the 75 material into a mold provided with such small crevices by means of a corner or gate, or even any number of such gates, as the metal would chill before it had run through many of the interstices. This difficulty is overcome by arranging the sprues V in the cover F directly opposite the openings of the mold formed by the notches T and the long notches B' in the ejector-bars E. The metal then need flow but little more than the thickness of the casting. 80 In fact, even with this construction it has been found desirable to heat the entire mold and the cover to just below the melting-point of lead, while the lead to be poured in is highly superheated. According to the construction 85 described the sprues are formed in the removable cover F, and they may be shaved off with a knife when the cover is removed.

One of the important features of my improved casting apparatus resides in the fact 90 that a seal is formed above and below the casting desired by the broad pad-leaf covers L, and a seal is formed at either side of the casting by the unnotched portions X of the ejector-bars and the top surfaces Y of the pad-leaves J. It may be stated that the spacing of the ejector-bars E need not be done by a separate series of separating-pieces K, permanently held in the main frame, because in any event the ejector-bars E always lie between 95 the pad-leaves J, which latter are never withdrawn sufficiently to allow the ejector-bars to collapse toward one another. After the casting is made the cover is pried off by hand by suitable means, as shown, a notch Z being 100 formed in the cover for the insertion of a hand-lever. After the cover is removed the sprues are shaved off by a suitable knife, and the pad-block is pried back by any suitable means, as by the levers a, provided with the 105 hooks b for insertion with the notches c in the pad-block, and the pad-block is pried back until the pad-leaves J have receded from out of the casting into the position of the parts 110 shown in Fig. 5. Suitable stops d limit the 115 backward movement of the pad-block. In order to eject the casting, the pad-block is again pushed forward, whereupon the tongues S of the pad-leaves J no longer enter readily and easily within the apertures D in the casting, 120 from which they have just been withdrawn, and therefore the casting is pushed forward and ejected from the mold.

According to my construction of mold the 125 castings are produced in a practicable man- 130

ner, the construction is simple, strong, and efficient, a multiplicity of parts is entirely avoided, leakage is prevented in a simple manner, and my whole construction has been 5 found to operate efficiently and well.

The description so far has embraced sheets 1 and 2 of the drawings, including Figs. 1 to 11, which illustrate the manually-operated mold. In the remaining figures an automatic casting-machine is shown and will be described, the principles of construction and operation of the mold being, however, identical with the construction and operation of the manually-operated casting-machine.

15 The objects of the automatic machine are to enable all the operations of casting to be automatically controlled, and in carrying out the construction of the machine means are provided for bringing the especially-constructed 20 mold up to a novel plate or nozzle through which lead is squirted by a properly-timed pump. After the casting has solidified the mold is withdrawn from the nozzle-plate, a 25 knife shaves off the sprues, a brush brushes off the chips from the knife, then the sprues and 30 pad-leaves of the mold are automatically withdrawn, and finally they are pushed back again, thus ejecting the finished casting from the mold. The machine then commences again in 35 its cycle of operations, and the operation is repeated anew. At all times water is squirted through the cored mold to chill it.

Referring now to Figs. 12 to 35, inclusive, *f* represents the bed of the automatic machine, 35 upon which are supported the frames *g*. The driving-shaft *h*, which may be suitably driven by hand or from a motor *i*, is connected by suitable means to drive the gear *j* upon the main shaft *k*, as shown, the driving-shaft *h* 40 being provided with a worm *l* and the gear *j* being a worm-gear meshing therewith. The main shaft *k* is connected to operate the crank-shaft *o*, as shown, there being a pinion *p* upon the main shaft meshing with a gear *q* upon 45 the crank-shaft *o*. The crank-shaft *o* is provided at one end with the crank *r*, and it is also provided with an adjustable cam *s*, controlling the operation of the pump in the pot *t*. Any suitable means may be provided for 50 operating the pump in the pot *t* and timing its operations to accord with the movements of the mold, as shown in this instance the pump-plunger *u* being connected to one end of the lever *v*, the other end of which is pivoted at 55 *w* to an arm supported from the frame of the machine. A spring *x* normally tends to pull the pump end of the lever *v* downwardly, while, as shown, there is a roller *y* pivoted upon the lever and bearing upon the cam *s*. 60 The cam is provided with a notch *z* and is angularly adjustable about the axis of the crank-shaft *o*, the cam-plate being provided with notches 1, through which extend the adjusting-studs 2 for changing the position of the 65 cam *s* upon its supporting-disk. The cam

raises and drops the pump-plunger through the operation of the lever *v*, and, as stated, the amount of travel of this plunger *u* and the length of time it is in its lowermost position are governed by the notch in the cam. 70

A timing of the pump motion with relation to the mold motion is governed by the rotary adjustment of the cam-notch on its hub. The mold is carried upon the rocking carriage-arm 3, pivoted about the shaft 4, suitably supported upon the bed *f* of the machine, and operative connections are provided for rocking the carriage-arm 3 by the rotation of the crank-shaft *o*. These operative connections are constructed to afford provision for moving the mold up to the nozzle of the pump and leaving the mold in such position for a portion of the revolution of the crank-shaft *o*, and means are provided for varying the time at which the carriage-arm 3 and the mold are 80 at rest during the revolution of the crank-shaft *o*. While various means may be provided for carrying out these objects, I have shown the crank *r* connected to the carriage-arm 3 by means of an adjustable rod 5, 85 a spring 6, and an adjustable arm 7. By varying the length of the arm 7 the length of the arc of travel of the mold may be varied, and by varying the length of the connecting-rod 5 the portion of a revolution during which 90 the mold is at rest may be varied. By varying these two elements—that is, the arm 7 and the connecting-rod 5—the apparatus may be adjusted and timed to a nicety.

According to the construction described 100 the arm 7, connected to the carriage-arm 3, is provided with slots 8, through which the adjusting-screws 9 extend, so that the length of said arm may be varied. The outer end of the arm 7 is provided with bearings for an 105 enlarged pin 10, provided with an aperture through which the end 11 of the connecting-rod 5 extends. Upon the connecting-rod are an elongated screw-threaded sleeve 12 and a locking-nut 13, the end of the collar 12 bearing upon the pin 10, which is slightly flattened to afford a bearing for the end of the sleeve 12. The sleeve 12 and lock-nut 13 are adjustable along the rod 5, and the spring 6 normally tends to pull the pin 10 against the end 115 of the sleeve 12, thus normally tending to pull the carriage-arm 3 toward the crank-pin. When the crank-shaft is rotated, the carriage-arm 3 is rocked toward the pump through the operation of the strong spring 6, which, as 120 shown, is connected to a portion of the carriage-arm. According to the construction described it will be seen that the connecting-rod 5 is not rigidly connected to the carriage-arm; but when the said carriage-arm has been 125 moved up to the pump and the mold is pressing against the nozzle-plate the connecting-rod 5 is free to slide relatively to the carriage-arm, in this case the spring simply being replaced under increased tension. Upon the re- 130

turn stroke of the crank the end of the sleeve 12 will be pressed against the pin 10 and push the carriage-arm and mold away from the pump. Since the pin 10 may rotate in its bearings, complete provision is afforded for a rotary motion of the crank and a rocking motion of the carriage-arm. The function of the spring 6 is to always hold the carriage-arm tight up against the nut 13 on the connecting-rod or 10 against the nozzle-plate of the pot. As shown, the carriage-arm is counterbalanced by the weight 14, carried upon the arm 15, connected to the carriage-arm, the weight being adjustable, and the angular position of the arm 15 being 15 also adjustable to make the counterbalancing perfect. The carriage-arm 3 is provided in this instance with two finished surfaces 16, to which as many molds as may be desired are secured. The construction of mold is in all 20 essential particulars substantially like the construction of mold shown and described in connection with the manually-operated apparatus, provision being afforded in the automatic machine for automatically retracting the pad-leaves J and for pushing them forward again to eject the casting.

As shown in Fig. 23, the mold comprises the frame 17, provided with the water-passage 18, with which the pipes 19 connect in 30 order to water-cool the mold. Within the frame 17 the pad-block slides, comprising, as before, the pad-leaves J', the separating-plates K', the pad-covers L', and the backing-plate R', as shown, the different portions of the pad-block being secured together as by means of suitable screws Q'. In this instance the backing-plate R' is extended and provided with a recessed portion or aperture 20, within which the upper end of the pivoted lever 21 operates 35 to withdraw the pad-block, the movement of which is limited by the stop 22.

The ejector-bars E', as before, are provided with the recesses B' and their outer ends are also recessed at 23, so that when the said ejector-bars are assembled in the mold and interleaved between the pad-leaves J' the notches or recesses 23 afford provision for securing the blocks or plates 24 therein, thus preventing both endwise and inward and outward 40 movement of the ejector-bars. Likewise strips or bars 25 are suitably secured at the ends of the ejector-bars E'.

In the perspective view shown in Fig. 20 the pad-block and ejector-bars E' are shown 45 assembled, with the pad-leaves thrust forwardly between the ejector-bars, a detail of this construction being shown in perspective in Fig. 28. It is obvious, however, that in assembling the parts of the apparatus the pad-block is first thrust within the casting or frame 17 and then the ejector-bars are interleaved between the pad-leaves. The frame 17 and pad-block and ejector-bars having been assembled, the whole is placed within the upper 50 end of the carriage-arm 3, as shown in Fig.

15, and suitably secured in position, as by the screws 26.

Small hubs 27 on the carriage-arm 3 above and below the mold serve as guides for the rods 28, which in turn carry the shaving-knife 29, that cuts off the sprues. The rods 28 at one end are fastened into the casting 30, which is connected by a short link 31 to the end of a bell-crank lever 32, pivoted on the stud 33, which is connected to the carriage-arm. On the 75 shorter end of the bell-crank lever 32 there is a roller 34, provided with a spherical periphery 35, this roller, as shown, sliding in a cam-slot 36 in a plate 37, fastened to the bed 70 of the machine. The backward motion of the carriage-arm 3 forces the roller 34 to descend in following the slot 36, thus moving the upper end of the bell-crank 32 outwardly and moving the plate 30, into which the ends of the knife-rods are fastened, outwardly, thereby drawing 80 the knife 29 across the face of the mold to cut off the sprues. The knife is pressed flat against the face of the mold by spring-washers or other suitable means mounted on the studs 38, carried on the knife-rods 28.

Means are provided for pushing the particles of material from the knife during an interval in which the knife rests at the end of its stroke after having moved across the face of the mold and cut off the sprues. The attachment for actuating the brush 38^a is mounted in this instance upon the cast-iron piece 30, which holds the knife-rods 28, and the construction of the brush mechanism is such that as the carriage-arm 3 moves backward the 90 brush 38^a is moved from the position shown in Fig. 14 downwardly across the knife 29. Then a slight twist or turn is given to the brush, moving it clear of the knife and out of contact with the same, so that upon the upward movement of the brush contact is not made with the knife and the knife-edge is left 95 clean and free from particles.

Any suitable mechanism may be provided for carrying out these objects, as shown, the 100 block 39 being pivoted to the casting 30 upon the pivot-pin 40, so that the block is free to revolve in a direction generally parallel to the plane of the knife. The shank 41 of the brush in this instance extends through the block 39 105 and is pivoted therein, so that the brush is free to turn through a limited angle about an axis substantially perpendicular to the axis 40, about which the brush as a whole revolves. A pin 42, Fig. 36, is connected to the shank 41, and the stops 43 and 44 limit the angle through which the shank 41 may revolve about its longitudinal axis. A short stud 45 is suitably connected to the shank 41 of the brush, and a loose link 46 extends down and is connected to the 115 bed of the machine at 47 for actuating the brush. As the carriage-arm 3 moves backward, the link 46, pulling upon the stud 45 of the shank of the brush, causes the said shank to rotate through its limited angle, thus bring- 120 125 130

ing the pin 42 against the stop 44. Further movement of the carriage-arm then rotates the whole brush and block 39 about the axis 40, sweeping the brush across the knife to clear it of chips. When the carriage-arm has completed its travel and is returning in the opposite direction, the link 46 commences to push against the small stud 45 on the brush-shank 41. The first effect of the push of the link 46 is to rotate the shank 41 and the brush about its longitudinal axis and bring the pin 42 against the stop 43, thus lifting the brush clear of the knife. Further movement of the carriage-arm then pushes the brush-shank and brush about the axis 40, thereby rotating the brush to its upright position without touching the knife. During the upward and forward movement of the carriage-arm 3 the knife 29 is moved back to its original position in readiness for again cutting off the sprues. The knife is moved backward, as described, as the small spherical roller 34 moves upwardly in the cam-slot 36.

As hereinbefore stated, a cam-lever 21, suitably pivoted at 48 upon the carriage-arm 3, is provided with a downwardly-extending arm 49, and a suitable spring 50, mounted rigidly on the carriage, bears at its outer end upon a flattened projecting portion of the pivot 48, tending normally to maintain the lever 21 in the position shown in Figs. 12 and 17. It will be seen that by rotating the lever 21 about its axis 48 against the tension of the spring 50 the pad-block will be withdrawn from the mold. A suitable stop, shown as a rounded piece of metal 51, is provided upon a support 52, secured upon the bed of the machine, and as the carriage-arm moves backward the tail of the lever 21 bears upon the stop 51 and the lever is rotated about its axis 48, thus withdrawing the pad-block. When the carriage-arm has moved sufficiently for the cores to have been withdrawn the proper distance and with the proper degree of leverage, the tail of the lever 21 trips over the fixed stop 51, and then the lever 21 is snapped back under the influence of the spring 50 to its normal position. The pad-block is then free to be pushed forward again to the position it occupied when the carriage-arm began to move away from the spout.

Suitable means are provided for returning the pad-block, as shown, a pad-stop 53 being provided upon the bed of the machine. The end 54 of the pad-block moves into contact with the stop 53 toward the end of the backward movement of the carriage-arm, with the result that the pad-block is pushed into the mold to eject the casting. The continued rotation of the crank-shaft then draws up the carriage-arm and mold back against the nozzle-plate of the machine with the mold in condition to receive the next squirt of metal.

As shown, the pad-stop 53 is adjustable longitudinally upon the bed *f* of the machine, the

screws 55, working in the slots 56 of the pad-stop, permitting such adjustment, so that the time in the backward stroke of the carriage-arm at which the pad-block abuts against the pad-stop may be varied. As shown, the stop 51 is also adjustable. The pot *t* in this instance is a single casting and contains the pump-cylinder 60. There is a channel 61, leading to the nozzle 62 of the pot, which is arranged at such an angle that it is parallel to the face of the mold when the latter is in position to receive the molten metal. The nozzle is held in position in any suitable manner, as by means of the screw 63, for supporting the nozzle from the nozzle-plate frame 64, whose function is to maintain the pot in alignment. At the back the pot-nozzle is provided with an aperture 65 and a plug 66, which may be withdrawn from the aperture to allow the dross in the nozzle to be cleaned out. In the top of the nozzle is a tube 68, adapted to be connected with an air-valve 69. (Shown in Fig. 35.) This valve is designed to admit air to the nozzle when the pump-plunger rises, so that the lead may recede freely from the back of the nozzle-plate 70; but when the pump descends the valve is closed and neither lead nor air can get through to the valve-tube. So far the nozzle acts as if no valve were connected with it. On the suction-stroke of the pump the lead in the nozzle would tend to remain there, since the melted lead has sealed all the vents, so that no air could reach the nozzle-chamber to permit the lead to descend without causing a vacuum. The valve permits air to reach the nozzle-chamber in this way, and therefore allows the lead in it to recede coincident with the up-stroke of the pump.

The nozzle-plate 70 is a composite plate, the inner or back half of which consists of a bronze plate 71 with two bronze lugs 72 extending backwardly through slots in the spout. The front face 73 of the nozzle-plate in this instance is of steel. The steel plate is riveted upon the bronze plate, and the composite plate thus formed is firmly secured, as by means of screws, to the nozzle. The nozzle-plate is perforated with several rows of inwardly-tapered holes 75 in order to enable the sprues to be readily withdrawn from the nozzle.

The function of the inner bronze half of the nozzle-plate and its lugs is as follows: The flame from the burner 74 plays upon the lugs 72, which being of highly-conducting material readily heat the flat bronze plate to such a temperature that the molten metal freely runs off it and does not solidify upon it. On the other hand, the metal in the tapered apertures 75 must be sufficiently solid to withdraw therefrom with the casting. The outer steel plate 73 is cooler than the inner bronze half 71, thus permitting the lead in the apertures 75 to solidify. The steel

plate 73 also prevents the mold from becoming overheated, since steel is a much poorer conductor of heat than bronze. Another function of the plate 73 is to prevent the cool 5 mold from chilling the bronze plate too much. Both the plates 71 and 73 may be constructed of materials other than those specified, I having mentioned the bronze or steel or iron as suitable materials, of which many others may 10 be found. It is desirable to avoid excessive heating of the body of the nozzle, and this end is accomplished in this instance by heating the nozzle through the medium of the conducting bronze lugs 72 instead of heating the 15 nozzle itself. The pot itself is heated by the main burner 76, which maintains the lead just above its melting-point and yet not sufficiently hot to permit it to oxidize or to cause it to cool slowly when squirted into the mold. 20 In this instance the bronze lugs 72 are caused to be heated by two burners 74, independent of the pot-burner 76, so that the lugs 72 may be considerably hotter than the body of the pot *t*. 25 The operation of the machine may be briefly recapitulated as follows: The pot *t* being filled with lead and brought to the proper temperature and the parts of the apparatus being also at suitable temperatures, power is applied 30 to drive the main shaft, and through the operative connections described the carriage-arm 3 is moved upwardly and forwardly until the mold is brought tightly against the face of the nozzle-plate 70. For a portion of the 35 revolution of the crank *r* the mold is left against the nozzle-plate 70, and the pump is so timed that the pump-plunger is moved downwardly under the action of the spring *x* to squirt the molten metal into the mold. The 40 carriage-arm is thereafter moved backwardly, and in the course of its backward movement the knife 29 is moved across the face of the mold, scraping off the sprues. While the knife remains at the farthestmost position of its 45 stroke the brush 38 is moved down across the knife to clean it of chips. The carriage-arm 3 continuing to move backward, the pad-block is retracted and then pushed forward again at the end of the backward stroke of the carriage-arm to eject the finished casting. As 50 the carriage-arm again moves forward to receive the next charge of material the brush 38 is moved upwardly to normal position and the knife is retracted to be in readiness to again scrape across the face of the casting.

It will be seen that by imparting a continuous rotary motion to the main shaft and crank-shaft an intermittent motion is given to the carriage-arm, and means are provided 60 for holding the carriage-arm tightly up against the nozzle while the metal is being squirted into the mold, and means are provided for properly timing the metal-squirting pump. The apparatus is constructed to afford provi-

sion for the unused metal to run back from 65 the inside of the nozzle and away from the back of the nozzle-plate. After withdrawing the mold, casting, and attached sprues from the nozzle-plate the subsequent mechanical operations, it will be seen, are carried out 70 through the movements of the carriage-arm alone.

It will thus be seen that according to my invention my improved mold for casting open-work structures comprises, essentially, series 75 of relatively movable interleaved plates, one series having recesses therein and the other series being provided with tongues. While I have chosen to term certain parts of my mold "pad-leaves" and "ejector-bars," I am not to 80 be understood as limiting myself in any particular by these terms, for they are to be understood in a general sense, and it is conceivable that many different forms of pad-leaves and ejector-bars may be devised for carrying 85 out the objects of my invention.

With my improved construction of mold I avoid the great difficulty which would be found in making the numerous fine rectangular slits in the bottom of a mold and fitting 90 the numerous tongues thereto, which would be necessary with a mold in which the tongues projected through apertures in the bottom of the mold. The tongues would have to be fitted on all four sides of each one, while in 95 my construction I can readily take up wear, and, as hereinbefore stated, there is no tendency to jam.

By varying the length of the arm 7 and of the connecting-rod in proportion the bearing 100 of the latter on the arm 7 may be made to have a motion to and fro exactly equal to that of the crank-pin, in which case the mold does not remain at rest for any substantial part of a revolution. By shortening the arm 7 and 105 connecting-rod 5 the distance traveled by the bearing on the arm 7 becomes less than the to-and-fro motion of the crank-pin, so that the main carriage-arm is at rest for such portion of a revolution as is consumed by the 110 crank-pin in receding from and approaching the bearing on arm 7 while at a distance from the latter greater than the length of the rod 5.

Obviously some features of my invention 115 may be used without others, and my invention may be embodied in widely-varying forms.

Therefore, without limiting myself to the construction shown and described nor enumerating equivalents, I claim, and desire to obtain by Letters Patent, the following:

1. A mold for casting open-work structures, comprising series of relatively movable interleaved plates, one series having recesses therein and the other series being provided with tongues, both said series of plates being of 125 greater length than the casting, whereby the

metal is prevented from leaking around the ends of the plates, for substantially the purposes set forth.

2. A mold for casting open-work structures, comprising relatively movable series of pad-leaves having tongues, and recessed bars interleaved between said pad-leaves, both said series of pad-leaves and bars being of greater length than the casting, whereby the metal is prevented from leaking around the ends of the leaves and bars, for substantially the purposes set forth.

3. A mold for casting open-work structures, comprising a series of recessed bars, separated by plates having tongues, the notches between the tongues being of substantially the same depth as the recesses in the bars, and the unnotched top surfaces of the plates co-operating with the unrecessed ends of the bars, to form a seal at each side of the casting, the bars and plates being movable relatively to each other, for substantially the purposes set forth.

4. A mold for casting open-work structures, comprising a series of recessed bars, separated by plates having tongues, the ends of which tongues are flush with the tops of the bars, the notches between the tongues being of substantially the same depth as the recesses in the bars, and the plates being movable relatively to the bars, whereby the tongues may be withdrawn from between the recessed portions of said bars, for substantially the purposes set forth.

5. A mold for casting open-work structures comprising a series of recessed bars separated by plates having tongues, the notches between the tongues being of substantially the same depth as the recesses in the bars, the bars and plates being movable relatively to each other, and a removable cover having sprues therein, for substantially the purposes set forth.

6. A mold for casting open-work structures comprising a series of recessed bars separated by plates having tongues, the notches between the tongues being of substantially the same depth as the recesses in the bars, the bars and plates being movable relatively to each other, and a removable cover having sprues therein arranged opposite the notches in the said plates to afford provision for rapidly filling all parts of the mold with metal, for substantially the purposes set forth.

7. A mold for casting open-work structures, consisting of a pad-block, comprising pad-leaves having tongues, and bars interleaved between the same, said bars having recesses of substantially the same depth as the length of the tongues, and the bars being of greater length than the pad-leaves, to afford provision for securing the bars to the frame of the mold, the pad-block being movable relatively to the bars, whereby the tongues on the pad-leaves may be withdrawn from between the recessed portions of the bars, for substantially the purposes set forth.

8. A mold for casting open-work structures comprising a series of pad-leaves having tongues formed in one edge by notches, and bars interleaved between said pad-leaves, and each provided with a continuous and uniformly-deep recess extending substantially the length of the notched portions of the pad-leaves and of substantially the same depth as said notches, the pad-leaves and bars being movable relatively to each other, for substantially the purposes set forth.

9. A mold for casting open-work structures comprising a frame provided with substantially parallel bars each having a continuous and uniformly-deep recess, and a pad-block comprising a backing-plate provided with pad-leaves having tongues arranged between the recessed portions of the bars, the frame and pad-block being relatively movable, for substantially the purposes set forth.

10. A mold for casting open-work structures, comprising pad-leaves, a portion of each of which is provided with tongues separated by notches, there being an unnotched top space at each side of the tongues, and ejector-bars interleaved between the pad-leaves, and each bar provided with a recessed portion having an unrecessed portion at either side of the recess, the unrecessed portions of the ejector-bars co-operating with the unnotched top surfaces of the pad-leaves, to form a seal for the metal at either side of the casting, and means for moving the pad-leaves and ejector-bars relatively to each other, for substantially the purposes set forth.

11. In a casting-machine, the combination of a nozzle and means for forcing molten metal therethrough, a mold for casting open-work structures comprising series of relatively movable interleaved plates, one series having recesses therein and the other series being provided with tongues, means for automatically bringing said mold up to the nozzle and withdrawing it therefrom, means for shearing off the sprues as the mold is withdrawn from the nozzle, and means for brushing the chips from the shearing-knife, for substantially the purposes set forth.

12. In a casting-machine, the combination with a nozzle and means for forcing molten metal therethrough, of a mold for casting open-work structures comprising series of relatively movable interleaved plates, one series having recesses therein and the other series being provided with tongues, means for automatically moving the series of plates having tongues from between the recessed plates, and then inserting said plates between the recessed plates again to eject the casting as the mold is withdrawn, for substantially the purposes set forth.

13. In a casting-machine, the combination with a nozzle and means for forcing molten metal therethrough, of a crank-shaft and crank, a carriage-arm carrying a mold, a rod

connected to the crank and slideable in a bearing relatively to the carriage-arm, and a spring connecting the carriage-arm with the crank, whereby provision is afforded for permitting the mold to rest at the nozzle during a portion of a revolution of the crank, for substantially the purposes set forth.

14. In a casting-machine, the combination with a nozzle and means for forcing molten metal therethrough, of a crank-shaft and crank, a carriage-arm carrying a mold, a rod connected to operate the carriage-arm from the crank-shaft in one direction and a spring connected to the crank-arm for operating the carriage-arm in the other direction, whereby provision is afforded for permitting the mold to rest at the nozzle during a portion of a revolution of the crank, for substantially the purposes set forth.
15. In a casting-machine, the combination with a nozzle and means for forcing molten metal therethrough, of a crank-shaft and crank, a rocking carriage-arm carrying a mold, an adjustable rod connecting the carriage-arm and the crank-shaft, means for adjusting the distance of the connection of said rod with the carriage-arm from the pivot of said arm, and a spring connecting the carriage-arm with the crank, for substantially the purposes set forth.
16. In a casting-machine, the combination with a pump and plunger for the molten metal, of a nozzle and nozzle-plate thereon, and a valve connected with said nozzle and constructed to admit air to the nozzle as the pump-plunger rises, whereby the metal may freely recede from the back of the nozzle-plate on the suction of the plunger, for substantially the purposes set forth.
17. In a casting-machine, the combination with a pump and plunger for the molten metal, of a nozzle and nozzle-plate thereon, and a

valve communicating with said nozzle and constructed to close when the plunger descends, and open to the atmosphere when the plunger rises, whereby the metal may freely recede from the back of the nozzle-plate on the suction of the plunger, for substantially the purposes set forth.

18. A mold for casting open-work structures, having relatively movable series of plates provided with tongues, and recessed bars interleaved between said plates, the depth of said recesses being constant, for substantially the purposes set forth.

19. In a casting-machine, the combination of a pivoted carriage-arm, actuating mechanism therefor, adjustable connections between said mechanism and the carriage-arm, and means for varying the distance of said connections from the pivot of the carriage-arm, for substantially the purposes set forth.

20. In a casting-machine, the combination of a movable mold, rotary actuating mechanism therefor, and means for adjusting the proportion of a revolution of said actuating mechanism occupied in actuating the mold, for substantially the purposes set forth.

21. A nozzle-plate for a melting-pot, having its inner face of highly-conducting material heated to a materially higher temperature than its outer face of a poorer conducting material, whereby the metal is prevented from chilling on the inner face while caused to chill on the outer face, for substantially the purposes set forth.

In testimony whereof I have signed this specification in the presence of two subscribing witnesses.

JOSEPH BIJUR.
